KEEPER INSERTING TOOL

Filed May 3, 1944

UNITED STATES PATENT OFFICE

2,431,636

KEEPER INSERTING TOOL

Charles A. Dougherty, Wilmington, Del.

Application May 3, 1944, Serial No. 533,879

3 Claims. (Cl. 81—5.1)

1

This invention relates to a tool for inserting the keepers of valve stems.

In internal combustion engines the valves are held under tension by springs which bear against washers slideable on the stem, and the latter telescope split keepers which encircle the stem. The insertion or removal of these keepers is a difficult problem due to fact that in most vehicles the engines are supported quite low down in the vehicle and the workman must depend upon his sense of feeling in inserting the keepers. An object of this invention is to provide a keeper inserting tool which will render insertion of the keeper certain and easy. Heretofore, tools of this kind have been provided but these prior tools have not found favor with mechanics because of the fact that the keeper were not properly gripped or positioned.

It is, therefore, another object of this invention to provide a keeper inserting tool which will hold the split portions of the keeper in outwardly divergent relation so as to provide for the ready encircling of the stem by the keeper.

A further object of this invention is to provide a tool of this kind embodying a pair of spring-pressed jaws and an intermediate jaw between the pair of jaws, the intermediate jaw being formed with outwardly divergent sides confronting the pair of jaws so as to thereby hold the two parts of the keeper in outwardly divergent relation.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail top plan partly broken away and in longitudinal section of a keeper inserting tool constructed according to an embodiment of this invention;

Figure 2 is a fragmentary sectional view taken on the line 2—2 of Figure 1;

Figure 3 is a sectional view on the line 3—3 of Figure 1;

Figure 4 is a fragmentary top plan partly broken away and in longitudinal section of a modified form of this invention; and

Figure 5 is a sectional view taken on the line 5—5 of Figure 4 of the intermediate jaw.

Referring to the drawings, and first to Figures

2

1 to 3 inclusive, the numerals 10 and 11 designate generally a pair of pivoted handles which are pivotally mounted on a pivot 13. The handles 10 and 11 are elongated and of hollow construction and are constantly urged apart at their rear ends by means of a U-shaped spring 12. The handle 10 has secured to the forward end thereof, a jaw member generally designated as 14 and the handle 11 has secured to the forward end thereof, a jaw generally designated as 15. The jaw 14 is of U-shape in transverse section as shown in Figure 3, having an upper wall 16, a lower wall 17 and a connecting wall or bight 18. The jaw member 15 is also of U-shaped configuration in transverse section, and is formed of an upper wall 19, a lower wall 20 and a connecting wall or bight 21.

The upper wall 16 of the jaw 14 is formed with a concave cutout 22 and the lower wall 17 is also formed with a concave cutout 23. The outer edge of the cutout 23 is disposed inwardly from the outer edge of the cutout 22 so as to thereby form a seat 24 on which the lower end of one-half of a keeper is adapted to engage. The jaw 15 is also formed with a concave cutout 26 confronting the cutout 22, the cutout 26 being formed in the upper wall 19 and the lower wall 20 is formed with a concave cutout 27. The outer edge of the cutout 27 is positioned inwardly from the outer edge of the cutout 26 so as to thereby form a second seat 28 on which the other half 29 of the keeper is adapted to engage.

In order to provide a means whereby the two keeper members 25 and 29 will be held in the cutouts 22 and 26, with their lower ends on the seats 24 and 28, respectively, I have provided an intermediate jaw generally designated as 30. The intermediate jaw 30 includes an elongated flat resilient wire or metal strip which is bent upon itself so as to form a pair of outwardly divergent jaws or sides 31 and 32. The jaw or side 31 confronts the jaw 12, and the jaw or side 32 confronts the jaw 15. The outer ends of the jaws 31 and 32 are connected together by an arcuate connecting member 33 having the concave side thereof outermost for engagement of the periphery of a valve stem 24. The convergent or inner ends of the jaw members 31 and 32 have extending laterally therefrom, extensions 35 and 36, respectively. The extension 36 has formed integral therewith an obtusely disposed elongated member 39 which extends rearwardly and is formed at its rear end with a substantially right angularly disposed and inwardly projecting stop member 40. A stop pin 41 is extended through

the opposite sides of the handle 10 at the forward end of the handle and at a point spaced inwardly from the outer edge 42 of the handle 10, so that the elongated slide bar 31 may slidily engage between the pin 41 and the outer edge or wall 42 of the handle 10. The handle 11 has secured transversely thereof, a stop pin 43 which is positioned inwardly from the outer side or wall 44 of the handle 11, and the elongated member or slide bar 39, slidily engages in the space between the pin 43 and the inside of the wall 44. The inner edges of the walls of the jaws 14 and 15 are outwardly divergent as indicated at 45 and 46, respectively, so that the outer ends of the jaws 14 and 15 will readily slide over the outer surface of the valve stem 34 during the insertion of the keeper members 25 and 29.

Referring to Figures 4 and 5, there is disclosed a tool which is formed of a pair of handles 47 and 48 which are similar to the handles 10 and 11. The handles 47 and 48 are pivotally connected together at their forward ends on a pivot 49, and the handle 47 has formed integral with the forward end thereof a jaw member 50. The handle 48 has formed integral therewith a jaw member 51, and the inner edges of the two jaw members 50 and 51 are formed inwardly convergent as indicated at 52 and 53, respectively. The jaw member 50 is formed U-shaped in transverse section similar to the construction shown in Figure 3, having a top wall 54 and a bottom wall 55. The top wall 54 is formed with a pair of cutouts 56 and 57 of concave configuration and the lower wall 55 is formed with a pair of cutouts 58 and 59. The cutouts 58 and 59 are of less depth than the cutouts 56 and 57 so as to thereby form seats for the inserts after the manner shown in Figure 3.

Jaw member 51 is U-shaped in transverse section after the manner shown in Figure 3 and includes an upper wall 60 having a pair of concave cutouts 61 and 62. The jaw 51 also includes a lower wall 63 having a pair of cutouts 64 and 65 which are of less depth than the cutouts 61 and 62. The cutouts 64 and 65 confront the cutouts 58 and 59 and the cutouts 61 and 62 confront the cutouts 56 and 57. The cutouts 56, 58, 61, and 64 are formed on a greater radius than the cutouts 57, 59, 62 and 65 so as to provide for holding or clamping different sizes of inserts between the two jaws.

An intermediate jaw member generally designated as 66 is slidably mounted on the pivot 49 between the two jaws 50 and 51. The intermediate jaw member 66 includes a body 67 having an elongated opening 68 through which the pivot member 49 extends. The forward end of the body 67 has formed integral therewith a substantially V-shaped head or jaw 69 having inwardly convergent opposite sides 70 and 71 confronting jaws 50 and 51, respectively. The outer end of the head 69 is formed with a concave cutout 72 which is adapted to engage the periphery of the valve stem after the manner in which the concave connecting member 33 engages the stem 34 in Figure 1.

In use and operation of this keeper inserting tool, the handles 10 and 11 are compressed or moved toward each other thereby opening the jaws 14 and 15. The intermediate jaw 30 is moved forwardly to the limit permitted by the stop members 38 and 40. At this time, the small end of the jaw formed by the sides 31 and 32 will be disposed adjacent the cutouts 22, 23, 26, and 27. The complementary portions 25 and 29 of the

keeper are then inserted in the cutouts 22 and 26 with the open sides thereof confronting each other and with their lower ends resting on the seats 24 and 28. The handles 10 and 11 may then be released so that the spring 12 will expand the handles and contract the jaws 14 and 15, so as to thereby tightly hold the keeper members 25 and 29 against the outwardly divergent sides 31 and 32 of the intermediate member 30. The concave connecting member 33 is then pressed against the periphery of the valve stem 34 and the tool moved forwardly so that the stem 34 will engage between the jaws 14 and 15. In view of the outwardly divergent position of the two keeper members 25 and 29, the outer edges thereof will initially contact with the stem 34 at substantially diametrically disposed points, and further movement of the tool forwardly will push the intermediate jaw 30 inwardly so that the intermediate jaw 30 will become disengaged from the keeper members 25 and 29 and these members will then encompass the stem 34. When the keeper members 25 and 29 are disengaged from the intermediate jaw 30, the jaws 14 and 15 will tightly clamp these keeper members about the stem and they may be engaged in the conventional annular groove which is formed in the stem to receive these keepers. The tension on the valve springs may now be released so that the valve washer may drop downwardly, and the washer at this time will engage the upwardly projecting portions of the keeper members 25 and 29, so that when the handles 10 and 11 are compressed toward each other to open the jaws 14 and 15, the upper ends of the keeper members 25 and 29 will be seated in the keeper socket formed in the valve washer.

While tools of this kind have previously been constructed, such tools have not found favor with mechanics due to the fact that the keepers were not held in outwardly divergent relation so that they could readily encompass the valve stem as the tool was pushed forwardly. The result of the prior tools was that the keepers would become released or snap out of the jaws and, for this reason, the prior tools have usually been discarded. However, with a tool as hereinbefore described, the keeper members will be firmly held about the stem until the valve washer has been lowered and due to the divergent positioning of the keeper members, prior to and during the insertion operation, the keeper members will readily slide over and about the valve stem and will be retained in encompassing position by the tension of the spring 12.

What is claimed is:

1. A valve keeper inserting tool comprising a pair of pivoted handles, a pair confronting jaws carried by said handles, said jaws being U-shaped in transverse section and the parallel walls of each jaw having arcuate cut-outs with the cut-out of one wall of less depth than the cut-out of the other wall, and a resilient intermediate jaw between said pair of jaws and movable lengthwise therebetween, said intermediate jaw having outwardly divergent opposite sides confronting said cut-outs, and an arcuate connecting bar connecting the outer divergent ends of said sides together.

2. A valve keeper inserting tool comprising a pair of pivoted handles, a pair confronting jaws carried by said handles, said jaws being U-shaped in transverse section and the parallel walls of each jaw having arcuate cut-outs with the cut-out of one wall of less depth than the cut-out of

the other wall, and an intermediate jaw between said pair of jaws and movable lengthwise therebetween, said intermediate jaw having a pair of outwardly divergent arms confronting said cut-outs, an arcuate connecting bar between the divergent ends of said arms, rearwardly divergent extensions carried by said arms, obtusely inclined bars extending rearwardly from said extensions, right angularly disposed inwardly projecting lugs carried by the rear ends of said latter bars, and 10 stop pins carried by said handles engageable by said lugs to limit the forward movement of said intermediate jaw.

3. A valve keeper inserting tool comprising a pair of pivoted handles, a pair of confronting jaws carried by said handles, said jaws being U-shaped in transverse section and the parallel walls of each jaw having arcuate cutouts with the cut-out of one wall of less depth than the cut-out of the other wall, and an intermediate jaw 20 slideable between said confronting jaws having a pair of outwardly divergent arms confronting said

cut-outs, an arcuate connecting bar between the divergent ends of said arms, rearward extensions carried by said arms, right angularly disposed inwardly projecting lugs carried by the rear ends of said latter bars, and stop pins carried by said handles engageable by said lugs to limit the forward movement of said intermediate jaw.
